UNITED STATES PATENT OFFICE.

ARTHUR H. HILL, OF NEW YORK, N. Y.

FOLDING TOOTH-BRUSH.

specification of Letters Patent. Patented May 14, 1918.

1,266,465.

Application filed August 18, 1917. Serial No. 186,895.

To all whom it may concern:

Be it known that I, ARTHUR H. HILL, a citizen of the United States, residing at New York, in the county of New York and State of New York, have invented new and useful Improvements in Folding Tooth-Brushes, of which the following is a specification.

This invention relates to improvements in toothbrushes, the primary object of the invention being to provide a toothbrush wherein the bristle holder is pivotally mounted upon a hollow handle forming a receptacle into which the bristle holder is adapted to be folded, whereby the brush may be disposed in compact form so as to be easily, conveniently and inconspicuously carried in the pocket or in a hand bag for use wherever desired.

A further object of the invention is to provide a toothbrush of the character defined wherein the bristle holder, when in folded condition, will be protected against the access of dust and dirt so as to be kept in a sanitary state, wherein provision is made to secure ample ventilation for the drying out of the bristles after use, and wherein provision is further made for holding the bristle holder securely in folded and unfolded positions.

A still further object of the invention is to provide a brush wherein the hollow handle serves as a reservoir for powder or other dentifrice into which the bristles may be dipped when desired, combined with means for normally closing the powder chamber and covering and protecting the powder therein.

The invention consists of the features of construction, combination and arrangement of parts, hereinafter fully described and claimed, reference being had to the accompanying drawing, in which:

Figure 1 is a side elevation, with parts broken away and in section of a toothbrush embodying my invention, showing the bristle holder folded.

Fig. 2 is a vertical longitudinal section of the same.

Fig. 3 is a rear end elevation.

Figs. 4 and 5 are transverse sections on the lines 4—4 and 5—5 of Fig. 1.

In the practical embodiment of my invention I provide a folding brush comprising a bristle holder 1 and a hollow handle 2 forming a reservoir or casing to receive the bristles when the bristle holder is in folded con-

dition. The bristle holder 1 consists of a back 3, of metal, bone, celluloid or any other suitable material, from the inner face of which projects the brush surface 4 composed of any desired kind of brush bristles. The back 3 is provided at one end with an offset tang 5 projecting beyond the inner face thereof to an extent coextensive with the extent of the bristles 4, and adjacent to this tang the back 3 is formed with an opening 6, for a purpose hereinafter described.

The handle 2 is of proper size to snugly receive the bristle holder and consists of a receptacle open at one side and end and formed of parallel side walls 7, a bottom wall 8 and a rear end wall 9, the handle being open at its top and forward end to receive the body and tang of the bristle holder. As shown, the tang 5 fits between the forward ends of the side walls 7 and is pivotally secured thereto by a pivot pin or member 10, on which the bristle holder is adapted to swing outwardly into longitudinal alignment with the handle for use and to swing backwardly into the handle so as to be folded in close compass for storage or transportation.

The side walls 7 are provided with longitudinal slits 11 at their forward ends, which slits extend a short distance inwardly therefrom to partially separate the forward portion of the bottom wall 8 from said side walls, thereby providing a yielding tongue 12. This tongue is adapted for co-operation with the flattened bottom and top surfaces 13 and 14 and corner portions 15 and 16 of the tang 5, to secure a desired spring action for holding the bristle holder in outspread and folded positions. The distance between the pivot point 10 of the tang and the faces 13 and 14 is somewhat greater than the distance between such pivot point and the upper surface of the tongue 12, when said tongue is in its fully elevated position, so that when the bristle holder is in its closed and open positions, respectively, the tongue is slightly depressed and bears frictionally upon the surface 13 or 14 to hold the brush in folded or open positions. In the movement of the brush from closed to open position, and vice versa, the corner surfaces 15 and 16 ride upon and depress the tongue 12, allowing the brush to be swung open or closed, as will be readily understood. The surface 14 is disposed below the plane of the outer or top face of the brush back 3,

whereby a shoulder 17 is formed to abut against the outer end of the tongue 12 between said tongue when the bristle holder is open, thereby forming a rigid backing for the bristle holder when in position for use. The major portion of the bottom wall 8, in the form of the invention shown in Figs. 1 to 5, inclusive, is depressed below the plane of the tongue 12 and the rear wall 9, thus forming a chamber, pocket or reservoir 18 to receive a charge 19 of dental powder or other desired dentifrice, the said bottom wall being preferably sloped or extending on an incline from the tongue 12 to the rear wall 9 to gradually increase the depth of the pocket.

Formed in the side walls 7 in longitudinal alignment with the tongue 12 are guide grooves 20 to receive the side edges of a sliding shield or cover plate 21, which is employed for closing communication between the hollow handle and powder chamber under normal conditions, and thereby preventing contact of the brush bristles with the dentifrice. The forward edge of this cover abuts against the inclined shoulder formed between the depressed portion of the bottom wall and the tongue 12 to close the forward end of the powder chamber, and the rear wall 9 is formed with a guide slot 22 through which the rear end of the sliding cover projects, such end of the sliding cover being formed with an enlargement or finger piece 23 whereby it may be gripped and moved to open or closed position. It will thus be understood that normally the slide will be interposed between the bristles of the folded bristle holder and the charge of powder contained in the powder chamber, whereby the powder will be protected and kept dry and out of contact with the brush bristles, and whereby the access of dirt and dust to the powder or escape of the powder from the chamber will be prevented. The tang 5 is adapted to be rocked upon its pivot 10, so that the back 3 may be depressed by pressure thereon of the finger, upon the withdrawal of the sliding cover 21, which action will be permitted by the yielding depression of the tongue 12, so that the brush bristles may be dipped into the powder to take up a desired amount therefrom preliminary to the use of the brush. In thus taking up a charge of powder, it will be understood that if desired the bristle holder may be swung open and the brush bristles preliminarily moistened to facilitate this operation. After the required amount of powder is taken up, the cover 21 is closed and the bristle holder swung open for use in an obvious manner.

In practice, the construction of the brush is such that the device as a whole may be made of comparatively small size, so that it may be conveniently carried in the pocket, 65 in a hand bag or any other suitable receptacle in an inconspicuous manner, while when the bristle holder is open or extended a brush surface of proper area for thoroughly brushing the teeth and a handle of sufficient length to be conveniently grasped will be afforded. It will, of course, be understood that the hollow handle or casing may be made of metal, celluloid, or any other suitable material, and that when the bristle holder and casing are made of metal they may be nickel-plated or otherwise suitably ornamented. The construction of the brush is also such that a neat and attractive, and if desired ornamental, article of this character will be produced. The length of the back 3 is such that when the bristle holder is folded the free end of the back 3 will terminate just short of the wall 9, leaving a ventilation space or passage 24. Thus when the bristle holder is folded or closed the openings 6 and 24 will be provided at the ends of the casing for the inlet and exit of air, which will circulate through the brush bristles, whereby the bristles will be allowed to dry out and kept in a sanitary condition.

Having thus fully described my invention, I claim:

1. A tooth brush comprising a hollow handle formed to provide a bristle inclosing chamber, and a dentifrice reservoir at the bottom of said chamber and formed by the walls thereof and coinciding in length therewith, a bristle holder pivotally mounted for movement to open and closed positions and adapted when in closed position to be disposed so that the bristles extend into said bristle chamber, said holder being yieldingly mounted so that the bristles may be depressed into the dentifrice reservoir, and a sliding partition separating and controlling communication between the chambers and against which the bristles normally abut in the closed position of the holder.

2. A tooth brush comprising a hollow handle forming a bristle receiving chamber and a dentifrice receiving chamber at the bottom thereof, said chambers being substantially coextensive in length, said handle also having guide grooves in its side walls and a guide opening in one of its walls, a bristle holder pivoted at one end to one end of the handle for movement to open and closed positions and carrying bristles adapted to project into the bristle chamber when said holder is in closed position, and a sliding partition plate movable in said grooves and guide openings and arranged when in closed position to be disposed between the bristles and the dentifrice contained in the dentifrice chamber.

3. A tooth brush comprising a hollow handle open at top and one end, said handle including a bottom wall, side walls and a rear end wall, the bottom wall having a forward spring tongue and a depressed portion

in rear thereof, said depressed portion forming a dentifrice chamber coextensive in length with the body of the handle, a bristle holder comprising a back carrying bristles 5 adapted to project into the handle when said holder is in closed position, said holder being provided at one end with a tang pivotally connected to the side walls of the handle above said spring tongue and having surfaces 10 for coaction with the tang to permit depression of the bristles into the dentifrice chamber when the holder is closed and to hold said holder in folded and extended positions, and a sliding partition movable longitudinally of the handle and adapted to 15 close communication between the bristles receiving chamber of the handle and the dentifrice chamber.

4. A toothbrush comprising a hollow handle open at top and one end, said handle

including a bottom wall, side walls and a rear end wall, the bottom wall having a forward spring tongue and a depressed portion in rear thereof, said depressed portion forming a dentifrice chamber, and said side walls 25 being provided with longitudinal grooves and the rear wall with a guide slot in line with said grooves, a sliding cover for the reservoir engaging said grooves and slot, and a bristle holder comprising a back carrying bristles and having a tang pivotally connected to the side walls of the handle above said spring tongue and having surfaces 30 for coaction with the tongue to permit depression of the brush bristles when the sliding cover is removed and to hold the bristle holder in folded and extended positions. 35

In testimony whereof I affix my signature.

ARTHUR H. HILL.
